Primary Examiner — Rosemary K Tarcza*Assistant Examiner* — Sanjeev Paul(74) *Attorney, Agent, or Firm* — IDP Patent Services; Olav M. Underdal(57) **CLAIM**

The ornamental design for a toroidal seating cushion, as shown and described.

DESCRIPTION

FIG. 1 is a top perspective view of a toroidal seating cushion;

FIG. 2 is a top view thereof;

FIG. 3 is a bottom view thereof;

FIG. 4 is a left side view thereof;

FIG. 5 is a right side view thereof;

FIG. 6 is a front view thereof; and,

FIG. 7 is a rear view thereof.

The broken lines shown in the drawings are included for the purpose of illustrating unclaimed portions of the toroidal seating cushion and forms no part of the claimed design.
